UNITED STATES PATENT OFFICE.

WILLIAM C. GALBRAITH, OF WILMERDING, PENNSYLVANIA.

INK-WELL.

SPECIFICATION forming part of Letters Patent No. 790,628, dated May 23, 1905.

Application filed January 24, 1905. Serial No. 242,479.

To all whom it may concern:

Be it known that I, WILLIAM C. GALBRAITH, a citizen of the United States of America, residing at Wilmerding, in the county of Allegheny and State of Pennsylvania, have invented certain new and useful Improvements in Ink-Well, of which the following is a specification, reference being had therein to the accompanying drawings.

This invention relates to certain new and useful improvements in ink-wells, and has for its object to provide a novel form of ink-well wherein pen, pencil, and blotter holders are provided, also receptacles for pen-points, pins, and the like stationery articles.

Another object of this invention is to provide novel means in connection with an ink-well for supporting pens whereby the drippings of ink from a pen that has just been used can be returned to the ink-well or the receptacle containing the ink.

With the above and other objects in view the invention finally consists in the novel construction, combination, and arrangement of parts, which will be hereinafter more fully described, and then specifically pointed out in the claims, and, referring to the drawings accompanying this application, like numerals of reference designate corresponding parts throughout the several views, in which—

Figure 1 is a perspective view of my improved ink-well. Fig. 2 is a vertical transverse sectional view of the same. Fig. 3 is a perspective view of an ink-well having a double capacity, and Fig. 4 is a vertical sectional view of the same.

To put my invention into practice I preferably construct my improved ink-wells of glass; but I do not care to confine myself to this material, as the wells can be readily made of any material that can be cast or molded into the desired form. The ink-well as constructed by me is substantially rectangular in form, and consists of a body portion the top of which is provided with a recess 1, and centrally of said recess I form a well 2, having a flange 3 around its top edges. The formation of the recess 1 provides a rear rib 4, and in this rear rib I form a recesses 5, prefer-

ably near the sides of said ink-well, and these recesses form pen-supports, the pens being stuck in the recesses 5 and supported vertically therein. Between the recesses 5 I provide the substantially semicircular recesses 6, the bottom of said recesses being connected by a by-pass 7 with the well 2, and the recesses 6 are adapted to support pens vertically therein and convey the drippings from said pens to the well 2. The recesses 6 and 5 are provided with flanges 8 to further support the pencils and pens that may rest within said recesses.

The reference-numeral 9 designates a groove that is formed in the top of the ink-well, transversely thereof, to support a pen or pencil and should it not be desired to insert the same in either of the recesses 5 and 6.

The reference-numeral 10 designates a suitable lid or cover, which is preferably formed of a material similar to the ink-well, and this lid or cover is adapted to fit down over the flange 3 of the well 2 and prevent any dirt or dust from settling in the ink or fluid carried by the well 2.

By referring to Fig. 2 of the drawings it will be observed that the well 2 only extends about midway of the body portion of the ink-well 1, and in the front and rear faces of the ink-well I provide the horizontally-disposed recesses 11, in which are slidably mounted drawers 12. Each drawer has its front face cut away, as indicated at 14, forming a central rib 15, which serves as a handle to move said drawers.

Directly beneath the horizontally-disposed recesses 11 I provide a slot 16, which extends transversely of the ink-well, and this slot is adapted to support one or more blotters.

Reference will now be had to Figs. 3 and 4 of the drawings, wherein I have illustrated an ink-well constructed similar to the ink-well illustrated in Figs. 1 and 2, with the exception that the ink-well is of a double capacity—that is, intended for ink of two distinct colors. It will of course be understood that the ink-well can be constructed with a plurality of wells 2, having pen-supporting recesses communicating with each well. In the ink-well

illustrated in Figs. 3 and 4 of the drawings the pen-supporting recesses 6 6 connect with their respective wells 22, and in case black and red ink is placed in the well one of the pen-supporting recesses communicates with the red ink, while the other recess communicates with the black ink.

It will be observed from the foregoing description, taken in connection with the drawings, that I have provided a novel form of ink-well wherein novel means is embodied for supporting pencils and pens and such stationery articles as generally accumulate or lie upon a desk, and while I have herein illustrated the preferred manner of constructing my improved ink-well it is obvious that various changes may be made in the details of construction without departing from the general spirit and scope of the invention.

What I claim, and desire to secure by Letters Patent, is—

1. An ink-well comprising a body portion having a well formed therein, said body portion having pen-supporting recesses formed therein, and communicating with said well said body portion having supporting-recesses formed therein, slidably-mounted drawers carried by said body portion, and means for sup-

porting blotters within said body portion, substantially as described. 30

2. In an ink-well, the combination with a body portion having a well formed therein, said body portion having pen and pencil supporting recesses formed therein, drawers slidably mounted in said body portion, means for supporting blotters within said body portion, and means for conveying the liquid contents of said pen-recesses to said well, substantially as described. 35

3. In an ink-well, the combination with a body portion having a plurality of wells formed therein, said body portion having a plurality of pen and pencil supporting recesses formed therein, said pen-supporting recesses adapted to communicate with said wells, 45 drawers slidably mounted in said body portion, suitable lids adapted to cover said wells, and means for supporting a plurality of blotters within said body portion, substantially as described. 50

In testimony whereof I affix my signature in the presence of two witnesses.

WILLIAM C. GALBRAITH.
